COMPUTER INQUIRY STATION

David G. Moore, Johnson City, and George F. Fahringer, Endicott, N.Y., assignors to International Business Machines Corporation, New York, N.Y., a corporation of New York

Application February 19, 1958, Serial No. 49,703

Term of patent 14 years

(Cl. D26—5)

Fig. 1 is a perspective view of a computer inquiry station, showing our new design, the opposite side being plain; and

Fig. 2 is a rear perspective view thereof.

The broken line showing of a representative typewriter is for illustrative purposes only.

We claim:

The ornamental design for a computer inquiry station, as shown and described.
